Primary Examiner — Dana K Weiland*Assistant Examiner* — JennyLou M Binas(74) *Attorney, Agent, or Firm* — Warner Norcross + Judd LLP(57) **CLAIM**

The ornamental design for a vacuum cleaner, as shown and described.

DESCRIPTION

FIG. 1 is a front perspective view of a vacuum cleaner showing our new design;

FIG. 2 is a front view thereof;

FIG. 3 is a left side view thereof;

FIG. 4 is a right side view thereof;

FIG. 5 is an enlarged top view thereof;

FIG. 6 is an enlarged view of the encircled portion in FIG. 1; and,

FIG. 7 is an enlarged view of the encircled portion in FIG. 2.

The details shown in broken lines form no part of the claimed design.

The details of the vacuum cleaner shown in broken lines form no part of the claimed design. The dot-dashed broken line in FIGS. 1-2 and 6-7 show the boundary of the enlarged view and forms no part of the claimed design.

1 Claim, 7 Drawing Sheets(56)
